GUIDE MECHANISM FOR ROLLING
SHUTTERS AND THE LIKE

Albert Egli, Como, Italy

Application November 8, 1938, Serial No. 239,467
In Great Britain September 30, 1938

3 Claims. (CL 20—53)

My invention relates to improvements in guide rails for rolling shutters fastened to the sash outside and to be used in combination with outwardly opening casement windows; and the objects of my improvement are, first, to afford facilities for lowering the shutter when the windows are open; second, to provide protection from atmospheric influences or from sunlight when the windows are open; and, third, to also provide the 5 said protection when the windows are closed.

I attain these objects by the guide rail assembly illustrated, by way of one form of invention, in the accompanying drawing, in which—

Fig. 1 is a vertical section through the window opening with open casements;

Fig. 2, a similar section with closed casements;

Fig. 3, a horizontal section through the window opening with open casements;

Fig. 4, a similar section with closed casements; 20 and

Fig. 5, a view of the window sash with the guide rails and to a larger scale.

The shutter, which is of known type and character, is wound upon the drum 1. The guide rails 2 terminate immediately above the casements 3. The guide rails 4 are disposed on the inside, and the guide rails 5 on the outside of the casements 3. The said rails 4 and 5 are disposed at exactly the same distance from the point of rotation of 30 the casements so that the rails 5 form an extension of the said rails 2 when the casements are closed, and the rails 4 form an extension of the rails 2 when the casements are open. The guide rails 4 are supported by hinges 7 which allow 35 one to project them outwardly into an inclined position by means of the toggles 8 and 9.

The holders 10 are articulated to the wall dowels 11 and serve for fixing the open casements on the outside of the house. The guide rails 4 and 5 are of such a cross-section as to form 40 a guide flange 12. Snugs 13 are secured to the shutter and engage the said flange 12, thus preventing a derailing of the shutter when projecting the lower portion of the latter outwardly.

45 My invention, as illustrated, permits of various modifications without, however, departing from the scope of the inventive idea proper.

What I claim and desire to secure by Letters Patent is:

1. A guide mechanism for rolling shutters and the like for casement windows opening toward the outside, comprising a pair of vertical guide rails between a winding drum and the top of the sash, a second pair of vertical guide rails secured to the inside of the casements, a third pair of vertical guide rails secured to the outside of the latter, a plurality of snugs secured to the shutter 5 and engaging the said rails; said guide rails being so arranged that the second pair of guide rails forms the extensions of the first pair of rails when the casements are open, and that the third pair of rails forms the extensions of the 10 first pair of rails when the casements are closed.

2. A guide mechanism for rolling shutters and the like of the class described comprising a pair of vertical guide rails between a winding drum and the top of the casements, a second and a third pair of such rails respectively secured to the inside and the outside of the casements and forming extensions of the said first pair respectively in the open and closed position of the casements, a plurality of snugs secured to the shutter 20 and in engagement with the said rails, and an articulation in each rail of the second pair permitting of an inclination of the lower portion of the shutter with the casements in the open position.

3. A guide mechanism for rolling shutters and the like of the class described comprising a pair of vertical guide rails of semi-open cross-section between a winding drum and the top of the casements, a second and a third pair of guide rails similar to the former respectively secured to the inside and the outside of the casements and forming extensions of the former pair respectively in the open and closed position of the casements, a plurality of snugs attached to the shutter and engaging the said rails, and means in each rail of the second pair permitting of an outward 25 inclination of the lower portion of the shutter with the casements in the open position.

ALBERT EGLI. 45
